APPARATUS FOR ASSEMBLING FRAMES

Herbert W. Neunherz, Gardner, Mass.

Original application June 20, 1935, Serial No. 27,614. Divided and this application December 5, 1936, Serial No. 114,427. Renewed October 3, 1938

2 Claims. (Cl. 78—49)

This is a division of my application Ser. No. 27,614, filed June 20, 1935.

The principal objects of the invention are to provide a machine for the convenient, expeditious, and exact assembling of frames made up of longitudinal and lateral members, each composed generally of two parts, as for example, a metal frame and a wooden box frame consisting of sides and ends; to provide a machine by which 5 wooden sides and ends can be secured in an absolutely definite relation to a four-sided frame of metal or wood without the use of screws or other fastening devices of an inexact nature; to provide means whereby a plurality of fastening devices, as rivets, are inserted in two pieces of material simultaneously so as to prevent the deflection of any of these fastening devices while being applied, as will be the case where screws are inserted individually in wood, thus affording 10 an opportunity for the first screw to be put in at a slight angle, thus throwing out the accuracy of the whole assembly; and to provide an arrangement of a plurality of riveting machines spaced at predetermined distances apart for placing the 15 rivets in the desired positions according to the above mentioned objects so that a studio couch frame and a bedding box frame, for example, can be assembled on the same series of machines.

Other objects and advantages of the invention 20 will appear hereinafter.

Reference is to be had to the accompanying drawings in which

Fig. 1 is a front elevation, somewhat diagrammatic in form, illustrating a series of riveting machines set up for the particular purpose of 25 assembling a studio couch frame and a bedding box to go with it;

Fig. 2 is a horizontal sectional view on the line 2—2 of Fig. 1;

Fig. 3 is a sectional view on the line 3—3 of Fig. 2;

Fig. 4 is a plan of the clutch mechanism for starting the operation of a riveting machine;

Fig. 5 is a plan of some of the riveting machines showing how they are securely and accurately screwed together and to a wall;

Fig. 6 is a front view of the same;

Fig. 7 is a perspective view of a jig for accurately boring the wooden part of the frame to 50 secure absolute accuracy of the spaces between the holes;

Fig. 8 is a transverse sectional view on the line 8—8 of Fig. 7, and

Fig. 9 is a perspective view of the jig used for 55 punching the holes in the metal frame.

This arrangement is provided for the purpose of riveting two pieces together in such a way that the riveting can be accomplished very expeditiously and with absolute accuracy and so that any two sets of such pieces can be absolutely alike. Couch frames, for example, can be made by this method with extreme accuracy so that they will all be absolutely alike, for the first time. The distances between rivets are previously designed to fit a set of riveting machines, as, 1, 2, 3, 4, 5 and 6, which are set up with their rivet heads at certain accurate distances apart.

The metal frames are punched in the proper places at exactly the right distances apart. The wooden pieces are likewise bored at exactly the same distances apart. The machines shown cannot be tripped unless these prior operations are performed exactly.

The frames shown are generally composed of an inner frame of angle irons and outer boards 20 9. The inner frame is first riveted together by rivets so as to constitute a solid rectangular frame. Then the boards 9 are riveted to this frame individually, but not necessarily directly fastened to each other.

In order to prepare for the finishing of the frame, one side at a time of the metal frame is prepared by punching holes in at predetermined distances apart. This is done by the use of a jig 45 having a series of stationary punch bushings 46, which, of course, are stationary.

The boards 9 are bored, one at a time, by the use of a boring jig comprising a bench 47 on which the board is accurately located. A template 48 is held in position by brackets 49. At 35 the same distances apart as the bushings 46 are located on the template the same number of boring bushings 50. Other bushings 51 are shown for other purposes. A plurality of drills 52 are simultaneously brought down through the bushings 50 or 51. Thus in one stroke four holes may be bored in a wooden piece to constitute the outer wall of the frame. The corresponding side of the frame is punched with one stroke. The two sets of holes are at exactly equal distances apart.

The machines 1, 2, 3, etc. are fastened together by turnbuckles 55 and rods 56 so that they can be rigidly and accurately connected and can be adjusted to preserve that accuracy. They are also rigidly and adjustably connected to a wall 50 57 behind by turnbuckles 58 and 59 in a similar way.

Fig. 1 shows several riveting machines 1, 2, 3, 4, 5 and 6 set up on a floor 7 at certain predetermined distances apart. These distances are 55

very important and they are not uniform ordinarily. Each one of these riveting machines is provided with a pilot pin 8 and they are set up with a definite horizontal distance between the 5 axes of the several pilot pins. These distances are selected so as to adapt this set-up of machines for doing whatever work may be desired.

In Fig. 1 a dotted frame 9 is shown which is placed on three of the pilot pins so that when 10 the three plungers 10 come down they will insert three rivets simultaneously in the frame. The frame preferably contains two pieces, the outer frame 9 and an inner frame. Rivets fasten these two pieces together in certain definitely located 15 places. In the position shown the frame extends down below the floor line through an opening 12 in the floor.

These riveting machines do not constitute in themselves a part of this invention. A well 20 known form of riveting machine is shown in which the plunger 10 is operated from a clutch 13 which can be set into operation by a hand lever 14 or by a foot treadle 15. The foot treadle is pivoted, as indicated in Fig. 3, and held up by a spring 25 16. When it is depressed, it pulls down a rod 17 which operates the clutch 13 to connect up the mechanism for operating the plunger 10 with a clutch section 18. This clutch section is fixed with respect to a pulley 19 operated by a power 30 belt 20. On the same shaft as the member 18 and 19 is a pinion 21 which operates a belt 22 for feeding the rivets. The other parts of the riveting machine are not shown.

For the purpose of permitting the riveting operations to be performed simultaneously, as indicated in Fig. 1, a bar 24 is laid across three or 35 four of the treadles 15 and each of these treadles is provided with an oscillatable hook 25 which, when placed in the position shown in Fig. 3, will cause these treadles to work together by the depression of one treadle. By reversing the hook 25 each machine can be operated individually. In the instance illustrated the depression of any 40 one of the three treadles of the machines 2, 3 and 45 4 will result in the simultaneous descent of their three plungers 10 and the simultaneous riveting together of the end members of which the frame 9 is composed.

It will be understood that when the frame 9 is turned a quarter of the way around, its side 50 will rest on four pilot pins of the four machines 1, 2, 3, and 4, but the operation will be substantially the same. It may be stated further that the two machines 5 and 6 are located at a definite 55 space from each other different from that of any other machines and that the space between the central lines of the machines 4 and 5 is a still different dimension. These two machines 5 and 6 are used in making another frame 60 but in the same way as that previously described.

In this case a frame is provided which comprises at the top the angle iron internal frame and the wooden frame 9 outside it. The machines 5 and 6 are shown as set up at proper 65 distances from the machine 4 for making the bedding box frame. The distance apart of the machines 4 and 5 is the distance between two rivets in the sides of the bedding box frame. The

distance between the machines 5 and 6 correspondingly is equal to the distance between two rivets in the ends thereof.

It will be seen that by this machine various kinds of frames consisting, not only of one set 5 of sides and ends, but having another rigid frame for connecting said sides and ends, can be formed expeditiously and with absolute exactness.

This invention is capable of use in making frames of other kinds than those specifically 10 illustrated and, in fact, is capable of a variety of uses for forming frames or corresponding parts of various articles. The number of riveting machines employed will depend, of course, on the complication of the article produced and in 15 many cases one of the machines can be eliminated if the distance apart of the rivets in the different frames can be made duplicates of each other. The first four machines can be employed alone for the manufacture of a single frame and 20 the other two machines will not then be necessary.

Frames made by this machine are not only exactly alike, as they come from the machines, but wooden frames connected in this way are 25 much stronger and more rigid than they could be made by fastening the wooden pieces directly together by means of screws or other fastening devices.

Having thus described my invention and the 30 advantages thereof, I do not wish to be limited to the details herein disclosed, otherwise than as set forth in the claims, but what I claim is:—

1. In an apparatus of the class described, the combination of a plurality of separate complete 35 riveting machines, each having a pilot pin and riveting plunger at the top, said pilot pins being located at predetermined distances apart, with the pilot pins in alignment, said pilot pins engaging in preformed openings in a single piece of 40 work consisting of a wood and a metal frame to locate the two frames with respect to said riveting plungers and enable the plungers to unite the wood and metal, a treadle for each riveting machine, means at the bottom for connecting 45 each treadle with the plunger for operating it, a bar located in contact with all the treadles, and latching means for positively connecting it therefrom, whereby several machines can be operated simultaneously to insert rivets in a single piece 50 of work, for the purpose described.

2. In an apparatus of the class described, the combination of a plurality of separate complete riveting machines, each having a pilot pin and riveting plunger at the top, said pilot pins being 55 located at predetermined distances apart, with the pilot pins in alignment, said pilot pins engaging in preformed openings in a single piece of work consisting of a wood member and a metal member to locate the two members with 60 respect to said riveting plungers and enable the plungers to unite the wood and metal, a treadle for each riveting machine, means for connecting each treadle with one plunger for operating it, whereby the machine can be operated to insert 65 rivets accurately in a single piece of work, for the purpose described.

HERBERT W. NEUNHERZ.
